Continuation of design applications Ser. No. 13,862, and Ser. No. 13,878, Oct. 7, 1968. This application May 1, 1969, Ser. No. 17,194

Term of patent 14 years

Int. Cl. D7—99

U.S. Cl. D49—34

FIG. 1 is a perspective view of a foldable bag-supporting stand in its erected condition, and showing our new design;

FIG. 2 is a side elevational view;

FIG. 3 is a perspective view showing the foldable bag-supporting stand in its folded condition;

FIG. 4 is a perspective view of a slightly modified form of foldable bag-supporting stand embodying our new design;

FIG. 5 is a side elevational view of the modified form of foldable bag-supporting stand shown in FIG. 4; and

FIG. 6 is a perspective view of a modified form of foldable bag-supporting stand in its folded condition.

The sides of the foldable bag-supporting stands not shown in the drawings are mirror images of the sides thereof shown in FIGS. 2 and 5 of the drawings.

This application is a continuation of our prior, co-pending design patent applications Ser. Nos. D. 13,862

and D. 13,878 filed Oct. 7, 1968 and now abandoned.

We claim:

The ornamental design for a foldable bag-supporting stand, substantially as shown and described.
